MANUFACTURE OF WEATHER-STRIP ELEMENTS

Robert C. Pierce, Niles, Mich., assignor to National Standard Company, Niles, Mich., a corporation of Michigan

Application March 30, 1935, Serial No. 13,979

26 Claims. (CL. 154—1)

This invention relates to the manufacture of weather strips, especially those used for automobile doors, and will be described as carried out with a novel machine which is adapted to operate continuously and automatically as long as supplied with the materials used.

An object of the invention is to improve the weather strip by embodying therein a novel and inexpensive but effective resilient means for 10 yieldingly holding the weather strip in sealing engagement with its door. I prefer to use resilient wire, which can be wound rapidly and accurately about a suitable core (of twisted tarred paper or other material) in such a manner as 15 to form a series of flat resilient loops approximately in the same plane at one side of the core.

An element of this type preferably has mounted thereon a slitted tubular cover (of rubber or 20 the like) which embraces and incloses the core, with the flat resilient wire loops projecting through the slitted side of the cover. Usually the entire weather-strip is then provided with a fabric cover, sewed or otherwise secured in 25 place, and which cooperates with the flat wire loops to form a resilient flange by means of which the weather strip is attached to the door frame or other support.

Various features of the invention relate to the 30 structure of the described weather strip, and to the method of making it which has been described above in general terms and which is hereinafter explained in detail.

Other important features of the invention relate 35 to a novel machine for manufacturing the above-described weather-strip elements. In the preferred construction, the core is fed lengthwise through an annular power-rotated member which carries a supply of wire, and which winds 40 the wire (under tension) continuously about the advancing core, and about a presser foot or the like which is advanced at the same speed as the core in a path paralleling but spaced from the core, thus forming the enlarged loops described 45 above. The presser foot may periodically, and preferably at a very much higher speed, be shifted toward the core to disengage it from the wire and then returned to its starting point.

The core with the wire so wound thereon then 50 advances to means, such as a novel series of rollers, for compressing the wire about the core and flattening the loops into substantially the same plane. I prefer to stretch the wire about the core so tightly that it is stretched beyond its elastic limit, so that there is no tendency to

spring back when it leaves the machine. These rollers in themselves embody certain features of novelty, further described below.

If desired, the core element so made may next be advanced to a novel mechanism which opens 5 up a slitted tubular cover, preferably of rubber, and then closes it about the core with the flat wire loops projecting through the slitted side of the cover.

The fabric cover may be secured about the 10 weather strip by a sewing machine of any desired construction, not necessary to be described herein, as standard commercial sewing machines are adapted to perform this operation.

The above and other objects and features of 15 the invention, including various novel constructions and operative steps and sequences, and various important specific arrangements and relationships, will be apparent from the following 20 description of the disclosure in the accompanying drawings, in which:

Figure 1 is a top plan view of that part of the machine which applies the wire to the advancing core;

Figure 2 is a side elevation thereof, looking 25 in the direction of the arrows 2—2 in Figure 1;

Figure 3 is a partial section on the line 3—3 of Figure 1, showing the drive means for the loop-compressing rollers;

Figure 4 is a perspective view of the principal 30 operative parts of the machine;

Figure 5 is a partial section on the line 5—5 of Figure 1, showing the means for tensioning the advancing core;

Figure 6 is an elevation of an alternative construction of wire-compressing rollers;

Figure 7 is a perspective view of the lefthand rollers of Figure 6;

Figure 8 is an elevation of an alternative form 40 of the rollers shown in Figure 7;

Figure 9 is a side elevation of the core element as it would look when held by the rollers of Figure 8, before being released from those rollers;

Figure 10 is a side elevation of the complete 45 machine;

Figure 11 is a diagram showing the successive addition to the core of the wire, the rubber cover, and the fabric cover;

Figure 12 is a section through the finished 50 weather strip, on the line 12—12 of Figure 11;

Figure 13 is a partial section of a part of a door and its frame, with the door closed and sealed by the weather strip;

Figure 14 is a partial section thereof just before the door closes; and

55

Figure 15 is a sectional view of a slitting means for operating on the rubber tubing.

Referring first to Figures 11 to 14, the novel weather strip comprises a continuous elongated cordlike element or a flexible core 10, of twisted tarred paper or the like, having formed thereon a resilient wire 12 parts 14 of which are compressed (and preferably stretched beyond the elastic limit of the wire so they will not spring back), and other parts of which are in the form of flat resilient loops 16 all approximately in the same plane.

A slotted tubular cover 18, of rubber or the like, encloses the core 10 and parts 14 of the wire, with the loops 16 projecting through its slotted side. A fabric cover 20 encloses the whole weather-strip. It has a seam 22 quite close to the rubber cover 18, and may if desired have one or more other seams where it projects outwardly on opposite sides of the flat loops 16, thus forming with said loops a resilient attaching flange for the weather strip.

A weather strip, made as described, may have its attaching flange tacked or otherwise secured 25 to the frame 24 of a door 26, in a manner well known with weather strips of this type. It has the advantage over most weather strips, however, that the attaching flange resiliently urges the enlarged edge portion of the weather strip 30 into sealing engagement with the door, and there is no tendency to spring away from the door.

Referring now to Figures 1-5, the core 10 is fed (from any desired source such as the reel 27 shown in Figure 10) lengthwise, past suitable 35 guides 28 and 30, under a tensioning shoe 32 pivoted on a horizontal lever 34 urged by an adjustable spring 36 in a direction to grip the core frictionally against the guide 28. It is drawn under tension from this friction drag by rollers 40 38 and 40 further described below.

Between the shoe 32 and the rollers 38 is arranged a spool 42 carrying the wire 12, which passes from the spool through a guide 44 and over a guide roller 46 and thence one or more times around a tensioning roller 48 held by a friction shoe 50, which guides the wire as it is wound around the core 10.

The spool 42, the guide 44, the roller 46, and the shoe 50, are all mounted on a rotatable annular member or ring 52 (Figure 2) arranged with the moving core 10 at its axis. The ring 52 has enlarged sides or annular shoulders 54 rotatably seated on and supported by three sets of anti-friction rolls 56 supported on the machine frame 58. The central part of member 52 is formed with gear teeth 60 drivably meshing with a sprocket chain 62 driven by a sprocket gear 64 (Figure 2) on a horizontal drive shaft 66 driven by a belt pulley 68 or other suitable means. As shown in Figure 10, the pulley 68 may be connected by a belt drive 70 to an electric motor 72 controlled by a switch or the like 74.

The shoe 50 is carried by one arm of a three-arm bell-crank lever 76 pivoted on the rotating ring 52. A second arm of lever 76 is connected to a coil spring 78, which is under substantial tension and which urges the shoe downwardly. The third arm of lever 76 carries a cam roller 80 which, at certain points in the machine cycle (e. g. during the withdrawal stroke of the presser foot described below, and during such time as wire is withdrawn most rapidly from the spool 42) successively engages cams 82, shown as adjustably mounted on the machine frame, there-

by relieving the pressure on the shoe 50. The upper cam 82 is removed in Figure 1, to avoid obscuring the parts below it, but is shown in detail in Figure 2. A suitable stop mechanism of any usual and desired type may be provided to stop the motor 72 if either the core 10 or the wire 12 should break.

The rotating ring 52 winds the wire around the advancing core 10 and around a presser foot 84 or the like which is adjustably mounted on a reciprocating slide 86 actuated by a double cam 88. The slide 86 is held yieldably against the cam 88 by a heavy tensioned coil spring 90.

The slide 86 reciprocates as a plunger in a carrier 92, best shown in Figure 4, which is mounted at its lower end on a pivot 94 and which has a cam roller 96 engaging a double edge cam 98 driven in synchronism with the cam 88.

The cams 88 and 98 are both driven from a shaft 100 (Figure 4) operated by a sprocket gear 102 driven by a sprocket chain 104 connecting it to another sprocket gear on the shaft 66. Thus the cams 88 and 98 are driven in synchronism with the wire carrier ring 52.

The cycle of the presser foot 84 is: (1) it is moved forward by cam 88 in a path paralleling but spaced from the advancing core 10 and at the same speed; (2) it is moved by a suitable spring (not shown) which holds roller 96 against the cam 98 a short distance toward the core 10, 30 to disengage it from the wire looped around it by the carrier 52, this being permitted by the shape of cam 98; (3) it is moved at a very much higher speed to the left in Figure 4, and then back a short distance away from core 10, to its initial position, ready to have the next loop of wire wound around it by the carrier 52.

If desired, cam 98 may be formed to move the presser foot 84 slightly away from the core 10 at the right-hand end of its stroke, to stretch 40 the wire looped around it and the core. With sufficient tension on the wire from shoe 50, this stretching movement is not usually necessary. As pointed out above, on the return stroke of the presser foot 84 the tension on the wire may 45 be relieved by cams 82.

The primary purpose of cams 82 is to relieve the tension on the wire 12 when wire is fed most rapidly from the spool 42 and the tension roller 48. This occurs during the 180° of revolution of the rotating ring 52 in which roller 48 moves on a path below a horizontal line through the core 10. During this portion of the cycle a length of wire approximately equal to the length of one of loops 16 is fed from the roller 48. The release of tension on roller 48 prevents breakage of the wire but sufficient tension is maintained by a friction shoe 106 on spool 42 to prevent overrunning or withdrawal of the wire. No breakage can occur under this tension because 60 the greater length of free wire is more resilient.

Two cams 82 arranged successively are shown. This construction gives a momentary tightening of wire 12 during the above-described half revolution of ring 52 sufficient to take up any slack 65 but not sufficient to cause breakage of the wire 12. If desired these two cams may be replaced by a single longer cam, thus relieving the tension on the wire 12 over approximately the whole period of rapid feed.

I prefer to provide the spool 42 with a friction shoe or drag 108 held by a spring 108. If spring 108 is light enough, it will not be necessary to relieve the pressure on shoe 108 at any time in the cycle; however, lever 110 carrying 75

the shoe 106 is shown with a third arm so that it may if desired carry a cam roller to engage a second stationary cam 82 (arranged in a different plane from the cam 82 which controls shoe 50, so that each of shoes 50 and 106 is controlled by its own cam only.

The core, with the loops of wire formed around it, next passes to the rollers 38, which have registering grooves receiving and embracing and compressing the core, and which crimp the loops tightly about the core, stretching it preferably beyond its elastic limit so there will be little tendency to spring back.

Referring to Figure 1 it will be seen that the apex of each successive loop 16 is held by the presser foot 84 until said loop is completely through the rollers 38, before said presser foot returns to pick up the next loop already formed about its rearward portion.

20 Figures 6 and 7 show an alternative form of roller made in two parts for manufacturing purposes only. Parts 112 have the necessary registering grooves for the core, immediately beside which are crimping rolls 114 having intermeshing 25 wedge-shaped projections and depressions, forming in effect peculiarly shaped gear teeth for the purpose of catching and holding each half of a loop 16 in the proper equi-angular relation with the axis of core 10.

30 In the case of wire so highly tempered that it does tend to spring back as mentioned above, I may substitute for rollers 38 the rollers shown in Figure 8. These rollers are similar to those shown in Figures 6 and 7 with the exception that 35 the arcuate surfaces 115 are not coaxial with the roller itself. This enables the rolls to crimp the wire above the core 10, past the desired final position, as shown in Figures 8 and 9, so that when it does spring back slightly after leaving 40 the crimping rolls the wire loops will be substantially in the same plane.

After leaving the crimping rolls 38, the wired core passes between rolls 40. These rolls 40 also have registering grooves embracing and compressing the core. At the side of these grooves (the right side in Figure 2) these rolls 40 have approximately cylindrical portions which flatten out the wire loops into substantially a single plane. I prefer to make these portions very 50 slightly conical, so that the rolls are slightly closer together at the apexes of the loops than adjacent the core 10, for example about .0015 inch closer. This is too small a dimension to appear in a patent drawing, but it does insure that the 55 apexes of the wire loops are properly flattened out.

The rollers 38 have intermeshing pinions 120 (Figure 3) one of which is driven by a shaft 122 having a worm wheel 124 driven by a worm gear 60 125 on the shaft 66. An idler 124 meshing with one of the pinions 120 drives somewhat larger pinions 126 operating the rolls 40.

The core 10, so provided with a series of flat resilient wire loops along one side, may then pass 65 through a guide 128 which twists it into a vertical plane, and thence over a spherically-surfaced roller 130 which opens up and feeds to it, from a reel 132 (Figure 10) or other suitable source, the slotted tubular rubber covering 18 previously 70 described. The cover 18 is closed again about the core 10, with the wire loops projecting through the slotted side of the cover, by two grooved folding rollers 134. Rollers 134 may be mounted on vertical shafts 136 having intermeshing drive

gears 138 and connected to the shaft 66 by suitable shaft-and-gearing connections 140.

It will be seen without further description that the advancing core 10 first has a series of wire loops formed about it and the presser foot 84, 5 that these loops are crimped about the core by rollers 38, the loops are then flattened by the rolls 40, and the cover 18 is next applied by rolls 130 and 134. The fabric cover 20, as previously noted, is secured in place by standard 10 sewing machinery.

If desired, a knife 150 (Figure 15) or the like, shown as heated by means indicated diagrammatically as an electric heating coil 152, may be mounted on the frame 58, with its point seated 15 in a recess in a bullet-shaped guide 154 carried by a suitable bracket 156 secured to frame 58, the knife and the guide cooperating to slit the rubber tubing as it passes from the reel 132 to the spherically-surfaced roller 130. 20

While one illustrative machine has been described in detail, it is not my intention to limit the scope of the invention to that particular machine, or otherwise than by the appended claims.

I claim:

1. A machine for making weather strips or the like comprising means for making a core having laterally-extending resilient means, means for supplying a non-metallic tubular cover, means for progressively slitting said cover along one 30 side, means for progressively opening the tube after it is slit, and means for applying said opened tube progressively to the side of the core opposite said means and progressively closing said tube about the core with said core arranged inside the 35 tube and said resilient means projecting through the slitted side of the tube.

2. A machine for making weather strips or the like comprising means for feeding a core, means for applying a resilient wire thereto with portions 40 encircling said core and securing the wire thereto and other portions projecting laterally in loops arranged approximately in the same plane, and means for assembling a tubular cover on said core with said loops projecting outside said cover. 45

3. A machine for making weather strips or the like comprising means for feeding a core, and means for applying a resilient wire thereto with portions encircling said core and securing the wire thereto and other portions projecting laterally 50 in loops arranged approximately in the same plane.

4. A machine for covering cores having laterally-extending resilient means comprising a feed roller having a curved surface and arranged 55 to open up a slotted tubular cover, and rollers for closing said cover up again with the core inside and the resilient means projecting through the slotted side of the cover.

5. A machine for covering cores having laterally-extending resilient means comprising means constructed and arranged to open up a slotted tubular cover, and other means for closing said cover up again with the core inside and the resilient means projecting through the slotted side 65 of the cover.

6. A method of making a weather strip core member or the like comprising feeding a flexible core lengthwise under tension, feeding a presser foot in a path paralleling but spaced from said 70 core, looping a continuous resilient wire about said core and presser foot, and compressing the wire loops at the core ends about said core leaving the other ends of said loops projecting laterally from the core in approximately the same plane. 75

7. A method of making a weather strip core member or the like comprising feeding a flexible core lengthwise intermittently feeding a presser foot in a path paralleling but spaced from said core and periodically shifting the presser foot toward the core and returning it to its starting point, looping a continuous resilient wire about said core and presser foot, and compressing the wire loops at the core ends about said core leaving the other ends of said loops projecting laterally from the core in approximately the same plane.
8. A method of making a weather strip core member or the like comprising feeding a flexible core lengthwise under tension, feeding a presser foot in a path paralleling but spaced from said core, looping a continuous resilient wire about said core and presser foot, and compressing the wire loops at the core ends about said core in a manner stretching the wire beyond its elastic limit so that it remains encircling and gripping the core, and leaving the other ends of said loops projecting laterally from the core in approximately the same plane.
9. That method of making a weather strip element which comprises winding a continuous wire about a moving core in a manner forming a series of loops much larger than the diameter of said core, and compressing said loops about the core leaving the excess wire projecting in flattened loops at one side of the core.
10. That method of making a weather strip which comprises winding a continuous wire about a moving core in a manner forming a series of loops much larger than the diameter of said core, compressing said loops about the core leaving the excess wire projecting in flattened loops at one side of the core, placing a tubular covering about said core with said flattened loops projecting therethrough, and securing a fabric cover over the tubular covering and over said flattened loops.
11. A machine for making weather strip elements or the like comprising an annular power-rotated member carrying a supply of resilient wire, means for feeding a core lengthwise through said member, a presser foot intermittently advanced at the same speed as said core in a path generally paralleling but spaced from said core and periodically shifted toward said core and then returned to its starting point at a speed much greater than its speed when advancing with the core, means whereby the rotation of said annular member winds wire from said source about said core and presser foot, and means for compressing the wire closely about said core with the portions which encircled said presser foot projecting laterally from the core.
12. A machine for making weather strip elements or the like comprising an annular power-rotated member carrying a supply of resilient wire, means for feeding a core lengthwise through said member, a presser foot intermittently advanced in a path generally paralleling but spaced from said core and periodically shifted toward said core and then returned to its starting point, means whereby the rotation of said annular member winds wire from said source about said core and presser foot, and means for compressing the wire closely about said core with the portions which encircled said presser foot projecting laterally from the core.
13. A machine for making weather strip elements or the like comprising means for feeding a core lengthwise, an element advanced in a path paralleling but spaced from said core, means for winding a wire about the advancing core and ele-
- ment, and means for compressing the wire about said core with the portions of the wire which encircled said element projecting at one side of the core.
14. A machine for making weather strip elements or the like comprising means for feeding a core lengthwise, means for winding a wire about the advancing core in loops much larger than the diameter of the core, and means for compressing the wire about said core with portions projecting in flat loops at one side of the core.
15. A machine for making weather strip elements or the like comprising means for feeding a core lengthwise, means for winding a wire about the advancing core in loops much larger than the diameter of the core, and means for compressing the wire about said core with portions projecting in flat loops at one side of the core, said means including rollers having registering grooves embracing and compressing the core with the encircling wire and also having approximately cylindrical portions at one side of the grooves to flatten said projecting loops.
16. A machine for making weather strip elements or the like comprising means for feeding a core lengthwise, means for winding a wire about the advancing core in loops much larger than the diameter of the core, and means for compressing the wire about said core with portions projecting in flat loops at one side of the core, said means comprising two pairs of rollers arranged in series, each pair having registering grooves embracing and compressing the core with the encircling portions of the wire.
17. A machine for making weather strip elements or the like comprising means for feeding a core lengthwise, means for winding a wire about the advancing core in loops much larger than the diameter of the core, and means for compressing the wire about said core with portions projecting in flat loops at one side of the core, said means comprising two pairs of rollers arranged in series, each pair having registering grooves embracing and compressing the core with the encircling portions of the wire, and the second pair also having at one side of said grooves approximately cylindrical portions arranged to flatten said loops.
18. A machine for making weather strip elements or the like comprising means for compressing about a core loops of wire which are much larger than the diameter of the core, and means for flattening the excess of wire into a series of loops projecting at one side of the core in approximately the same plane.
19. A machine for making weather strip elements or the like comprising rollers having registering grooves for embracing and compressing about a core loops of wire which are much larger than the diameter of the core, and other rollers having approximately cylindrical portions for flattening the excess of wire into a series of loops projecting at one side of the core in approximately the same plane.
20. A machine for making weather strip elements or the like comprising rollers having registering grooves for embracing and compressing about a core loops of wire which are much larger than the diameter of the core, and other rollers having approximately cylindrical portions for flattening the excess of wire into a series of loops projecting at one side of the core in approximately the same plane, said other rollers having the approximately cylindrical portions formed on a slight taper so that they are closer together at the side opposite said core.

21. Means for compressing about a core a wire wound thereon in loops which are much larger than the diameter of the core, comprising rollers having intermeshing wedge-shaped projections and recesses formed to force one side of each loop of wire past the other side, to stretch the wire about said core, with the remaining portions of the loops projecting at one side of the core. 5
22. A machine for covering cores having laterally-extending resilient means comprising means constructed and arranged to open up a slitted tubular cover, and other means for closing said cover up again with the core inside and the resilient means projecting through the slitted side 10 of the cover, together with cutting means ahead of the opening means arranged to slit the tubular cover lengthwise along one side.
23. A machine of the class described comprising means for feeding lengthwise a continuous element, means for supplying wire, and means for securing wire supplied by said supplying means about and at one side of said element in a series of loops larger than the element and which includes means to compress the loops to form flat 15 portions projecting laterally from the element.
24. A machine of the class described comprising means for feeding a cordlike element lengthwise, a part spaced from said element as it is fed, means for winding a wire in a series of connected loops about and at the side of said element and said part, and means to compress said loops to form flat portions lying substantially in the same plane. 5
25. A method of making the article described 10 which comprises feeding lengthwise a cordlike element, looping a continuous wire about said element and another element spaced from the first element and compressing said loops to form flat portions substantially in the same plane. 15
26. A method of making the article described which comprises feeding lengthwise a cordlike element, and looping a continuous wire about and at one side of said element in a connected series of flat loops and compressing said loops to 20 form flat portions projecting laterally from the element.

ROBERT C. PIERCE.
